HAY RAKE

Adolph J. Sync, Coldwater, Ohio, assignor to
New Idea, Inc., Coldwater, Ohio, a corporation
of Ohio

Original application November 25, 1935, Serial
No. 51,408. Divided and this application De-
cember 9, 1936, Serial No. 114,982

6 Claims. (Cl. 280—33.10)

This invention relates to hay rakes of the side delivery type, the invention relating more particularly to improvements whereby the tongue may be shifted laterally with respect to the machine; this application being a division of my pending application filed November 25th, 1935, Serial No. 51,408.

In the pending application referred to it was explained that in the raking of certain crops, particularly the crops from which it is intended to thresh seed, such as clover, beans and the like, if one of the horses is forced to walk on an edge of a window, or if one of the wheels must travel on a portion of a windrow, it is desirable to shift the wheel axially sufficiently to clear the windrow and also to move the tongue laterally so that the horse may likewise clear the windrow, it being clear that the rolling action of the wheel and the trampling of the horse on the seed pods breaks the pods and the seed loss is then comparatively heavy. In the pending application referred to the means for shifting the wheel is described and claimed and the present application is confined to the means for shifting the tongue.

An object of the present invention is the provision of means whereby the shifting of the tongue can be quickly and easily performed and the retaining means for the tongue removed and reapplied easily and quickly.

A further object of the invention is to provide improved means for permitting the adjustment of the tongue laterally with respect to the machine.

35 Referring to the drawing:

Fig. 1 is a top plan view showing my improved shiftable tongue applied to the frame of the rake, a portion of which is shown conventionally.

40 Fig. 2 is an enlarged fragmentary transverse section on the line 2—2 of Fig. 1.

Fig. 3 is a transverse section on the line 3—3 of Fig. 1.

45 Fig. 4 is an enlarged fragmentary longitudinal section on the line 4—4 of Fig. 3.

Fig. 5 is an enlarged fragmentary longitudinal section on the line 5—5 of Fig. 3.

50 Fig. 6 is a view mainly in perspective with some of the parts broken away to show details in section, of one portion of the connection of the shiftable tongue with the main frame of the rake.

As explained in my pending application referred to, the necessity and advantage of shifting a drive wheel indicates that a shifting of the tongue in the same direction is just as ad-

vantageous and necessary. The advisability of making a shift of the tongue may appear several times in a day's operation; therefore, an operator should be enabled to make the shift of the tongue as quickly and easily as possible and the device by which the tongue is retained in its shifted positions should be readily releasable to permit the tongue to be moved and as readily replaced to retain the tongue in place. In the present instance the construction not only permits of a quick shifting of the tongue, but also by simple means permits of a very quick detachment of the tongue proper from the machine which is advantageous when the machine is to be stored away.

Referring to the drawing, the tongue itself, in the present case, is the wooden member fragmentarily shown at 40. Across the rear end of the tongue 40 is secured an angle iron member 41 of a sufficient length that the effect is to distribute the pull on the frame to separated points as will be seen. Two tongue braces 42 and 43 are employed, one each being secured as by welding, or other means, at a point such as indicated at 44, Fig. 2, to each end of the cross member 41, then bent diagonally towards the tongue to which they are bolted at their forward ends by the bolt 45, Figs. 1 and 3. The rearward end of each of the diagonal braces 42 and 43 is formed into an eye; one only of these eyes is shown in full lines, it being the eye 46 (Figs. 4 and 6). The other eye is shown in dotted lines in Fig. 1 and is formed in the same manner except that it is on the reversed hand, and as can be seen in Fig. 1 the axis of each eye is in a vertical plane.

The connection of the tongue thus constructed with the frame of the machine is as follows: At two fairly well separated points on the forward rail 47 of the main frame 1 are secured in parallel relation to the rail 47, two round rods 48 and 49, tubular in the present case for lightness in weight. Each of these rods is secured at each of its ends to the vertical forward side of the rail 47 by bolts 50, the bolts passing transversely through the rods near the ends thereof and through the vertical leg of the forward rail 47, and through saddle members 51 interposed between the rods and the rail to provide a spaced apart relation of the rods and the rail.

Since as will be explained, the spaced apart eyes 46 of the tongue 40 are connected with the rods 48 and 49, the length of the rods depends on the amount of shift desired for the tongue, and the disposition of the pair of rods along the

rail depends on where it is desired that the draft animals are to walk. The tongue is detachably and slidably connected with the rods by the use of U-shaped clevises indicated in general at 52, 5 an idea of the longitudinal cross-section and therefore of its general form probably being best obtained from Fig. 5. Referring especially to Fig. 5 it can be seen that the U-bend portion of the clevis as indicated at 53 encompasses the 10 rod 49 about one-half its circumference, and that the upper leg 54 and lower leg 55 of the U-bend are in the present case spread apart to receive the eye 46 on the end of the brace 43. The detachable connection of the eye with the clevis 52 is by means of a pin 56 which passes through aligned openings in the legs 54 and 55 and through the eye 46. To further strengthen the connection, the upper leg 54 of the clevis is extended as at 58 to lie over the upper surface of 15 the cross member 41 at the point of the welded connection of the diagonal brace 43 therewith. A pocket is formed to receive the extended portion 58 of the clevis 52 by the securing on the upper surface of the cross member 41 at the end 20 thereof a strap 59. As seen best in Fig. 2 the strap member 59 is secured as by rivets 60 to the cross member 41, and is then bent upwardly as at 61 (Figs. 2 and 6) and horizontally as at 62 to lie over the end of the cross-member 41 and 25 downwardly as at 63 to complete the pocket.

Referring to Fig. 6 which shows one of the connections of the tongue with the frame, it will be clear that to detach the tongue from the machine, the cotters such as 64 are removed from 30 the pins 56, the pins are withdrawn from the clevises, and the tongue drawn forwardly, leaving the clevises hanging on the rods, from which the clevises may be finally removed if desired. To attach the tongue to the machine, each of the 35 clevis extended portions 58 is entered into its respective pocket and the tongue is moved rearwardly until the eyes are aligned with the openings in the clevis legs 54 and 55, after which the pins are inserted and retained by the cotters 64.

From this it will be seen that there is provided 40 a hingeable connection of the tongue with the machine, obtained through the direct connection of the clevises with the rods, and that also the tongue may be moved laterally by a sliding movement from side to side as indicated by the three 45 positions shown in full and broken lines in Fig. 1. To retain the tongue in any one of the three positions as desired is the function of the member now to be described. This member engages one 50 of the clevises 52, and as one only is needed, the clevis near the shiftable wheel 3 is the one to be engaged, as when an operator is shifting 55 this wheel, he can also very readily shift the tongue, it having been stated that in almost all cases where it is advisable to shift the wheel it is also preferable to shift the tongue.

The tongue retaining member is formed of suitably heavy flat sheet metal, and is loosely mounted 60 on the upper surface of the forward rail 47. In the present case, this loose connection is by means of three pins, two shorter pins 65 passing through openings 66 (one only being shown in Fig. 4) in the flat portion 67 of the retaining member and through the horizontal leg of the 65 forward rail, these openings being somewhat larger than the rivets to provide the desired looseness, and a longer pin 68 also passing through the retainer and the rail. In each of the shorter pins 65 near the lower end thereof there 70 is transversely inserted a cotter pin 69 (Figs. 4

and 5) at such a distance from the lower surface of the horizontal leg of the rail 47 as to provide the space 70, so that the retainer may be lifted to the extent of the space 70, and to hold the retainer down on the rail, a spring 71 surrounds 75 the longer pin and is interposed between the lower surface of the horizontal leg of the rail 47 and a transversely inserted cotter 72 bear the lower end of the longer pin.

The forward portion of the tongue retainer is 10 bent downwardly as at 73 to the extent that its forward edge almost makes contact with the rod 49 (Fig. 4) and since the length of the retainer is less than the space between the saddle members carrying the rod 49 by twice the width of 15 the clevis (Fig. 1), it can be seen that by disposing the retainer centrally between the saddle members, that a space is left between each end of the retainer and an adjacent saddle member, which space will accommodate the clevis. In 20 this manner, the tongue is held at either extreme of its possible movement.

To shift the tongue, it is only necessary to lift the tongue retainer, the retainer hinging to a certain extent on the shorter pins so that the 25 forward bent edge is lifted against the action of the spring 71. The extent to which it is lifted is merely sufficient that the forward depending edge 73 clears the clevis as shown by the broken lines in Fig. 5, after which the tongue may be 30 slid laterally along the rods. In order to enable the operator to conveniently lift the retainer, a lifting tab is formed in the center of the forward edge as indicated at 74, the space left by turning upwardly the lifting tab being made wide 35 enough to receive the clevis whereby a central position for the tongue is obtained as shown by the full lines in Fig. 1, the broken lines showing the position of the tongue when the clevis is being retained between the clevis and a saddle 40 member, or at its extremes of position. When the tongue is placed in the desired position, the retainer is released, the spring returning the retainer to its normal position and holding the tongue against displacement by vibration.

It will then be seen that with the construction as described, there is provided a simple, effective and durable retaining means for holding the shiftable tongue in any of its possible positions, and one in which the time of operation is held 50 to a minimum.

By this arrangement the shift is readily made in contrast with the earlier forms amounting to dismantling and reassembling some portion of the machine for it can be seen that when it is 55 understood that the advisability for shifting either the wheel or the tongue, or both, may occur several times in a day's operation, that the operation of shifting either or both of these elements will likely be deferred until a later time or 60 postponed entirely if the operation can only be done at the expense of a great deal of time or labor.

Having thus described my invention, I claim:

1. In a hay rake, a main frame, a pair of 65 spaced-apart rods secured to the forward portion of said frame and lying substantially parallel therewith, a tongue, a cross member attached to the rear end of said tongue, a pair of braces connecting said tongue with each end of said 70 cross member, a clevis pivotally and slidably mounted upon each of said rods, means for detachably connecting each clevis with the rear end of one of said braces, and a retaining member supported by said frame for retaining one of said 75

clevises in any one of a plurality of positions on its corresponding rod.

2. In a hay rake, a main frame, a pair of spaced-apart rods secured to the forward portion of said frame and lying substantially parallel therewith, a tongue, a cross member attached to the rear end of said tongue, a pair of braces connecting said tongue with each end of said cross member, a clevis pivotally and slidably mounted on each of said rods, said cross member having a pocket at each end to receive one of the legs of a clevis, means for detachably connecting each clevis with the rear end of one of said braces, and a retaining member supported by said frame for retaining one of said clevises in any one of a plurality of positions on the corresponding rod.

3. In a hay rake, a main frame, a pair of spaced-apart rods, means for securing said rods to the forward portion of said frame in substantially parallel relation therewith including a pair of saddles at each end of each rod, a tongue, a cross member attached to the rear end of said tongue, a pair of braces connecting said tongue with each end of said cross member, a clevis pivotally and slidably mounted upon each of said rods, means for detachably connecting each clevis with the rear end of one of said braces, and a retaining member for one of said clevises comprising a yieldable plate supported by said frame and positioned centrally of the length of one of said rods and forming spaces between the ends of the plates and the respective saddles of that rod to receive and retain said clevis, said plate also having a central notch to receive said clevis.

4. In a hay rake, a main frame, a pair of spaced-apart axially-aligned rods secured to the forward rail of said frame, a detachable tongue, a cross member secured to the rearward end of said tongue, a brace member attached to each side of the tongue forwardly of the cross member and secured at each end of said cross mem-

ber and extending rearwardly thereof, the extended portion of each brace member being formed into an eye, a pocket formed at each end of said cross member, a U-shaped clevis having one leg longer than the other pivotally and slidably depending from each of said aligned rods, each of said clevises adapted to embrace an eye of one of said braces, each of said clevises having an aligned opening in each of its legs to register with the eye of the corresponding brace, a removable pin insertable through the said openings of each clevis and through the eye of the corresponding brace, and a spring-pressed retaining member attached to the forward rail adjacent one of the said aligned rods to engage one of said clevises in any of a plurality of positions thereof on the corresponding rod.

5. In a hay rake, a main frame, a tongue, a device laterally shiftable with respect to said frame for connecting said tongue and frame, means for supporting the shiftable device from the frame, a movable retaining member carried by said frame formed to provide intermediate spaced engaging surfaces to engage the ends of said device to retain it in a central position, and being further provided with an engaging surface on each end thereof to engage and hold said device to one side of the central position between the retaining member and said supporting means.

6. In a hay rake, a main frame, a tongue, a laterally shiftable device for connecting said tongue and frame, means for supporting the shiftable device from the frame, and a movable retaining member carried by said frame having a free front edge formed to engage said device to hold the latter in a central position and having side edges each formed to engage and hold said device to either side of said central position between the retaining member and supporting means when the same is shifted.

ADOLPH J. SYNCK.
